UNITED STATES PATENT OFFICE.

JOHN T. MYERS, OF CULMERSVILLE, PENNSYLVANIA.

CUTTER-BAR FOR MOWING-MACHINES.

SPECIFICATION forming part of Letters Patent No. 703,806, dated July 1, 1902.

Application filed March 3, 1902. Serial No. 96,459. (No model.)

To all whom it may concern:

Be it known that I, JOHN T. MYERS, a citizen of the United States of America, residing at Culmersville, in the county of Allegheny and State of Pennsylvania, have invented certain new and useful Improvements in Cutter-Bars for Mowing-Machines, of which the following is a specification, reference being had therein to the accompanying drawings.

10 This invention relates to certain new and useful improvements in knife-bars for mowers, and said knife-bar being secured in an ordinary cutter attached to mowers of the well-known construction.

15 The present invention has for its object to provide a series of removable blades in the knife-bar, means to securely lock said knives in position, and means to permit the knives to be easily removed for the purpose of sharpening or replacing one of the blades in case they are broken.

Another object of the present invention is to provide a knife-bar of the above-described character that will be extremely simple in its 25 construction, strong, durable, comparatively inexpensive to manufacture, and highly efficient in its use; furthermore, to provide a device that will positively lock the cutter-blades permanently and that the jar incident to devices of this kind will not loosen the blades, as would otherwise be the case.

With the above and other objects in view the invention consists in the novel construction, combination, and arrangement of parts 35 to be hereinafter more fully described, and specifically pointed out in the claims.

In describing the invention in detail reference is had to the accompanying drawings, forming a part of this specification, and where- 40 in like numerals of reference indicate like parts throughout these several views, in which—

Figure 1 is a top plan view of my improved knife-bar, showing the securing-plate partly broken away. Fig. 2 is a vertical sectional view and a front view of the same. Fig. 3 is an end view. Fig. 4 is a detail view of the locking means and showing the parts disconnected.

In the drawings the reference-numeral 1 45 represents the knife-bar, which carries an up-

ward extension 2, having an inwardly-extending beveled face 3. This knife-bar 1 carries a series of upwardly-extending lugs 4, these lugs having a beveled under face 5, extending to the contracted or neck portion 6. This 55 knife-bar 1 also has formed therein an opening 7 to receive a head 8 of the screw-threaded locking-bolt 9. The knives or cutter-blades 10 are constructed so as to snugly abut against one another when arranged in proper position. These cutter-blades have formed at their abutting sides openings 11, which engage the lugs 4. A locking-bar 12 is secured above the cutters, which also has formed therein a number of slots 14, through which 60 the lugs 4 extend. This locking-bar carries a beveled end 15 to engage the beveled face 3 of the knife-bar, and at its opposite end a spring 16 is provided to engage the toothed nut 17, secured to the end of the screw-threaded bolt 9, and a securing-nut 18 engages the extreme end of the screw-threaded bolt, securing the parts together.

The manner of placing the knives upon the knife-bar is as follows: The knife-blade is 75 first secured under the beveled slide 5 of the lug 4, and then the opposite side of the knife may be easily placed over the square end of the lug, thereby placing it in proper position. When all the knife-blades have been placed 80 in position, the locking-bar is then placed over the lugs 4 and the nut 17 tightened, thereby drawing the knife-bar and locking-plate in opposite directions and engaging the locking-plate under the beveled side 5 of the 85 lug 4, thus securely locking the knife-blades in proper position and preventing the upward displacement thereof and the lugs serving to prevent the lateral displacement of the same.

In order to remove one or more of the 90 knives, the locking-bar is first removed, and then all or any of the cutter-blades may be removed for the purpose of sharpening or replacing the same.

The many advantages obtained by the use 95 of my improved device will be readily apparent from the foregoing description, taken in connection with the accompanying drawings.

It will be noted that various changes may 100

be made in the details of construction without departing from the general spirit of my invention.

Having fully described my invention, what 5 I claim as new, and desire to secure by Letters Patent, is—

1. The combination of a knife-bar having one of its ends provided on its upper face with an extension having a beveled under face, a 10 series of vertically-arranged lugs carried by the said knife-bar, a series of removable cutter-blades arranged on said cutter-bar, a locking-bar provided with a series of slots to receive the upper ends of the said lugs, and having one of its ends beveled and arranged under the said extension, and means whereby 15 said knife-bar and locking-bar are locked together.

2. The combination with a knife-bar and a 20 series of lugs arranged thereon, said lugs having elongated upper ends provided with beveled under surfaces of a series of cutter-blades arranged between the said lugs, a locking-bar provided with a series of openings to 25 receive the upper ends of the said lugs, a locking-bolt arranged between the said knife-bar and locking-bar, said locking-bolt pro-

vided with an angular head seated in an opening in the knife-bar, and a nut on the outer end of the said bolt.

3. The combination with a knife-bar having one of its ends provided on its upper face with an inwardly-projecting extension, said extension having a beveled under face, and a series of lugs arranged on said knife-bar, and 35 provided with elongated upper ends having beveled under faces, of a series of cutter-blades arranged between the said lugs, a locking-bar provided with a series of slots to receive the upper ends of the said lugs, and 40 having one of its ends beveled and arranged under the said extension, a locking-bolt arranged between the said knife-bar and locking-bar and provided with an angular head seated in an opening in the knife-bar, a nut 45 on the outer end of the said bolt, and means for preventing the rotation of the said nut, substantially as described.

In testimony whereof I affix my signature in the presence of two witnesses.

JOHN T. MYERS.
